UNITED STATES PATENT OFFICE.

FRANK CURTIN AND HENRY CURTIN, OF GLOVERSVILLE, NEW YORK, ASSIGNEES TO
CURTIN-HERBERT CO. INC., OF GLOVERSVILLE, NEW YORK, A CORPORATION OF
NEW YORK.

PINNING AND NAILING MACHINE.

Refiled for abandoned application Serial No. 635,427, filed April 30, 1923. This application filed January 29, 1925. Serial No. 5,664.

To all whom it may concern:

Be it known that we, FRANK CURTIN and HENRY CURTIN, citizens of the United States, residing at Gloversville, in the county of Fulton and State of New York, have invented certain new and useful Improvements in Pinning and Nailing Machines, of which the following is a specification.

10 Our invention relates to pinning and nailing machines, and is particularly applicable to machines which are designed to insert the pins or nails which are used to rivet in place the metal frames of pocket-books, hand bags, and satchels; or other articles in which metal parts are to be riveted to leather or fabric, the object of this invention being to produce a machine for the purpose above described, which will be more positive in action than those now in general use.

15 Our improvements lie particularly in the method of removing the pins or nails, one at a time, from the feeding tube which conveys them, heads up, from the usual hopper; in the method of inverting them so that the heads thereof will be down; and in the method of conveying them, so inverted, to a position where they will be 20 acted upon by a plunger which is adapted to force them upwards and through the parts to be pinned or nailed.

25 We accomplish our objects by means of an improved pinning and nailing machine, constructed substantially as hereinafter described, and illustrated in the accompanying drawings, in which:

30 Fig. 1 is a plan view of a pinning and nailing machine embodying our improvements.

Fig. 2 is a side elevation of same, parts broken away.

35 Fig. 3 is an enlarged side elevation, partly in section, of that portion of the machine wherein our invention particularly lies.

The same reference characters refer to the same parts throughout the several views.

40 Referring to the drawings, which are in a certain sense illustrative only, it will be seen that our improved pinning and nailing machine comprises a table 2, which may

be supported in any suitable manner as by the legs or standards 3, and that above the table is mounted a rotating hopper 4, adapted to be driven from the shaft 5, and to load pins and nails deposited therein into a gravity feed tube 6.

45 Mounted beneath the rear portion of the table 2, in suitable bearings 7, is a cam shaft 5, having mounted thereon a series of cams 8, 9, 10, and 11. One end of the shaft 5, is preferably provided with a hand wheel 12, and on this shaft is loosely mounted a pulley 13, adapted to be connected to a source of power (not shown). A clutch 14, provides means for causing the rotation of the pulley 13, to be communicated to the shaft 5, so as to drive said shaft, and any mechanisms connected therewith. The clutch lever 15, of the clutch 14, is connected by a rod 16, to any suitable operating means (as a stirrup, or a pedal bar, not shown).

50 Against the lower or discharge end of the feed tube 6, we mount, rotatively, a disc 17, the face of which is provided with a number of grooves 18, of a size adapted to receive one perfect nail or pin 19, and to exclude a second.

55 The back of the disc 17, is provided with suitable ratchet teeth 20, adapted to be engaged by a pawl 21, mounted on a pivoted lever 22, so that a reciprocating motion imparted to said lever will cause the disc 17, to be rotated to bring successive grooves 18, into alignment with the discharge opening in the end of the feed tube 6. A second pawl, 23, prevents reverse motion of the disc 17, and a shield 24, prevents the escape of a pin or nail fed into a groove in said disc until said nail reaches a point diametrically opposite that at which it entered said groove; when it reaches that point it is inverted, and is allowed to slide 60 out of said groove and enter, head down, a funnel-shaped opening 25, formed through the plate 26, mounted on the table 2.

65 To impart a reciprocating motion to the lever 22, so as to cause rotation of the disc 17, we pivot at 44, a double ended lever 45, the front end of which is slotted and engages with a spherical portion 46, formed on the lever 22, the rear end thereof being

normally forced downward by springs 47. A limiting stop 48, is preferably provided.

The reverse motion of the lever 45, is caused by a side of the lever 49, (also hinged 5 at 44) coming into contact with a projection 50, on the lever 45, motion being imparted to said lever by a pin 51, in the slide bar 30. As thus arranged, the motion of the slide bar 30, will normally control the motion of the lever 45, and the parts operated thereby or connected therewith.

The ratchet teeth 20, on the disc 17, and the pawl 21, on the lever 22, being adapted to rotate the disc on the upward motion 15 of the lever 22, in case an imperfect nail is fed into a groove in the disc 17, as the tension of the spring 47, is the only power tending to turn said disc, no destructive force will be applied. The only result will 20 be stoppage of the rotation of the disc 17, until the imperfect nail is removed.

Rotatably mounted on the table 2, and beneath the plate 26, is a disc 27, provided with a series of equally spaced holes 28, said 25 holes so spaced from the center of the disc as to come successively into alignment with the discharge end of the opening 25, when the disc 27, is rotated. The periphery of the disc 27, has notches formed therein 30 adapted to be engaged by a pawl 29, mounted on a reciprocating slide bar 30, so that the reciprocation of said bar will cause the rotation of said disc. The slide bar 30, is actuated by a cam 8, on the shaft 5.

35 Mounted beneath the front edge of the table 2, is a slideway 31, in which is a cross-head 32, in the upper end of which is mounted a plunger 33, the upper end thereof being adapted to pass through the openings 40 28, in the disc 27, and an opening 34, in the plate 26, and to force a pin or nail which may be located therein strongly upward to the limit of its travel. The cross-head 32, is actuated by a double ended lever 45 54, the required motion being imparted to the rear end thereof by a cam 9, mounted on the shaft 5.

Spring operated gripping means adapted to hold a nail or pin in the position in 50 the opening 34, in which it is left by the placing stroke of the plunger 33, (as illustrated in Figs. 2 and 3) are provided. The object being to hold the nail so that a pierced metal part may be easily threaded 55 on the end of the nail before the presser foot descends and the nail is driven upward to a seat.

To resist the upward thrust of the nail, so as to cause it to pierce the material to 60 be nailed and be firmly seated, we arrange a presser foot 35, the contact point 36, which is hollow (as shown in Fig. 3). The stem 37, of the presser foot extends below the table 2, and connects with one end of, and 65 is actuated by, the double ended lever 38,

the required motion being imparted to the rear end thereof by a cam 10, mounted on the shaft 5.

In order to accommodate different thicknesses of work, the downward motion of the 70 driving end of the lever 38, is communicated to the presser foot through a spring 39. Suitable means are provided for adjusting the position of the contact point 36, of the presser foot 35. 75

In order to assure proper alignment of the holes 28, in the disc 27, at the time the plunger 33, is to be forced upward therethrough, we provide a spring actuated locking mechanism 40, the pointed locking pin 80 41, passing through a hole in the plate 26, and entering one of the holes 28, in the disc 27, will force said disc into, and hold it in, proper position to bring one of the holes 28, into alignment with the plunger 33. The lock is released when it is desired to rotate the disc 27, by forcing the mechanism upward against the tension of the spring 42, the upward motion being imparted thereto by the double ended lever 43, the rear end thereof being actuated by a cam 11, on the shaft 5. 85

It is to be understood that pawls are to be provided with suitable springs to insure proper contact, although they may not be illustrated in the drawings. 90

We will now describe the manner in which our improved machine operates.

A quantity of pins or nails having been 100 placed in the hopper 4, and power applied to drive the shaft 5, the pins or nails will be loaded into the feed tube 6, in the usual manner, and will slide down said tube, hanging by their heads, until they reach the discharge end thereof. (Any type of 105 hopper which will properly load the nails or pins into the feed tube may be utilized).

It is of course obvious that the machine will not fully function until a sufficient 110 number of pins or nails have been fed into the mechanism to establish a condition such as is illustrated in Fig. 3, when there is a nail clutched by the spring operated gripping means located in opening 34, in the 115 plate 26; a nail in each opening 28, in the disc 27, in the rear of the one in which the plunger 33, is shown and ahead of the one under the opening 25; and a nail in each groove 18, in the disc 17, ahead of the one 120 into which a nail has just entered and behind the groove out of which one is just dropping.

The parts of the mechanism are so timed that at the end of each cycle the condition 125 will be as above illustrated, providing always that there is no failure of the nail supply, and no blocking of the disc 17, by reason of imperfect nails.

A cycle of the machine may be divided 130 roughly into four sections. With the ma-

chine in the condition just described and as illustrated in Fig. 3, a piece of work to be pinned being placed over the point of the nail or pin 55, and the clutch thrown in, the 5 first section of the cycle will cause the presser foot 35, to be lowered so as to press against the work, the plunger 33, to be forced upward and to seat the nail in the work. The second section of the cycle will cause the presser foot to be lifted, and the plunger to be withdrawn to its lowest limit. The third section of the cycle will release the lock, and cause the two discs 17, and 27, to be rotated forward one step, 10 which permits another nail to enter a groove in the disc 17, and a nail (inverted) to drop out of the diametrically opposite groove into the funnel-shaped opening 25. At the same time an empty hole in the disc 15 27, is presented under the opening 25, and a filled one (one with a nail therein) over the plunger 33. The fourth section of the cycle first permits the locking mechanism to locate and lock the disc 27, then forced upward 20 the plunger 33, until it reaches the position illustrated in Fig. 3, when the cycle is completed.

We claim:—

1. In a machine of the class described, a 30 table; a hopper supported above said table; an inclined feed tube leading from said hopper; a disc with a series of spaced radial grooves in the face thereof, rotatively mounted adjacent the discharge end of said tube; means for causing step rotation of said disc; a guard to prevent egress of a nail from said grooves during a major portion of their downward travel; a second disc rotatively mounted below said grooved disc 35 and having a series of circumferentially spaced holes therethrough; means for causing step rotation of said second disc; means for locking said second disc; means for releasing said locking means at intervals; a plunger slidably mounted beneath said second disc and in line with one of the holes therethrough when said disc is locked; a work supporting member with an opening therethrough to pass said plunger; yielding gripping means mounted adjacent said opening and adapted to grip a nail placed therein; a presser foot with an opening 40 therein; means for raising and lowering said presser foot; and means for imparting reciprocating motion to said plunger.
2. In a device of the class described, a 45 table; a hopper supported above said table; an inclined feed tube leading from said hopper; a disc with a series of spaced radial grooves in the face thereof, rotatively mounted adjacent the discharge end of said 50
3. In a machine of the class described: a table; a disc having a series of radial grooves formed in the face thereof, rotatively mounted above said table; means for causing step by step rotation of said grooved disc; means for delivering nails, head up, to successive grooves as they reach a position in the upper arc of rotation; a second rotatively mounted disc having a series of circumferentially spaced holes therethrough 55 adapted to receive nails discharged, head down, from said grooved disc; means for causing step rotation of said second disc; and means for forcing nails out of the holes in said second disc and into and through the work.
4. In a machine of the class described: a 60 table; a nail inserting plunger; a disc having a series of radial grooves, formed in the face thereof, rotatively mounted above said table; means for causing step by step rotation of said grooved disc; means for delivering nails, head up, to successive grooves as they reach a position in the upper arc of rotation; a second step by step rotating member, with a series of holes therethrough, adapted to receive nails discharged from said grooved disc and deliver them to the nail inserting plunger; and means for preventing the escape of nails from the grooves in said grooved disc until they reach the proper delivery point in the lower arc of rotation.

In testimony whereof we have affixed our signatures.

FRANK CURTIN.
HENRY CURTIN.
